UNITED STATES PATENT OFFICE.

MARY RUSSO, OF OLD ORCHARD, MAINE.

FORM FOR DRESSING HAIR.

Application filed March 12, 1921. Serial No. 451,734.

To all whom it may concern:

Be it known that I, MARY RUSSO, a citizen of the United States, residing at Old Orchard, in the county of York and State of Maine, have invented a new and useful Improvement in a Form for Dressing Hair, of which the following, together with the accompanying drawings, is a specification.

My invention relates to forms for dressing hair, and has for its object to provide a device of the above described character by the use of which hair may be dressed and held in such a manner as to give a shapely contour to the head.

15 A further object of my invention is to provide a form so constructed that the hair when once dressed thereon will not slip off, and in addition will be so supported that the coiffure will always retain its slighty 20 appearance, even after it has been disturbed, as for example, by putting on or taking off a hat.

These and other advantageous features 25 of my invention will hereinafter more fully appear, reference being had to the accompanying drawings, in which—

Figure 1 is a view in side elevation showing my improved form applied to the head of a wearer.

30 Figure 2 is a rear view of the head shown in Fig. 1.

Figure 3 is a view in end elevation of my improved form detached from the head of the wearer.

35 Figure 4 is a plan view of the form shown in Fig. 3.

Figure 5 is a view in side elevation of the form shown in Fig. 3.

Similar reference figures refer to similar 40 parts throughout the different views.

The form generally comprises a framework 1 which is adapted to fit the top of the head of the wearer, as indicated in Figs. 1 and 2. The framework 1 consists of articulated members 2 and 3 which are secured together by end members 4 and 5 and a plurality of cross members 6, 7 and 8, the whole providing a general crown-like structure adapted to rest easily on the head of the 45 wearer. The specific structure of the framework 1 forms no part of the present invention, and it is obvious that various modifications may be made in the arrangement of the several members.

50 I am aware that forms having the general arrangement of the framework 1 have here-

tofore been employed for dressing the hair and that such forms are often objectionable, for the reason that they tend to give the hair a too set appearance, owing to the inherent rigidity of the form. Furthermore, the hair is liable to slip off the form, particularly when it is disturbed by putting on or taking off a hat. By my invention I propose to provide a hair form which is yieldable and at the same time is adapted to always hold the hair in place under all conditions.

To this end a plurality of hair supporting members 9, 9, are secured to the framework 70 1, the members 9 arching over the cross members 6, 7 and 8, as shown clearly in Fig. 3. The hair supporting members 9 are crimped so as to present a wave like contour and are secured at their ends to the members 4 and 5 of the framework 1, so as to permit of pivotal movement with respect to the framework 1. The supporting members 9 are here shown as being connected to the end members 4 and 5 by merely wrapping the ends of 75 the members 9 around the members 4 and 5, as indicated at 10, so as to form a hinge like connection, but it is obvious that the members 9 may be secured to the framework 1 in other ways in order to permit of movement thereof. The supporting members 9 normally extend upwardly from the framework 1 at an angle to each other, as indicated in Fig. 5.

When using my improved hair form it is 90 first placed on top of the head after lifting the hair so as to permit the framework 1 to rest almost on the scalp. The hair is then arranged over the supporting members 9 in any desired manner, the strands of hair being distributed among the serrations of the members 9 so as to give a smooth and uniform appearance to the coiffure. The ends of the hair may then be tucked in beneath the form or secured in any suitable manner 95 in accordance with the taste of the wearer.

From the foregoing it is apparent that I have provided a form which is adapted to support the hair above the scalp at a number of places, the hair supporting members being so formed as to prevent displacement of the hair after it has once been dressed thereon. It is obvious that when a hat is placed upon the head of the wearer and is pressed into position thereon, the hair supporting 105 members 9 will tend to spread apart, as indicated in dotted lines in Fig. 5, and thus

allow the whole coiffure to yield, without, however, disturbing its general contour. After a hat has been placed in the desired position, the members 9 will tend to return 5 to their normal position, and thus help hold the hat in place without the use of hat pins. Furthermore, when the hat is removed the supporting members 9 will return to their original position, as shown in full lines in 10 Fig. 5, and thus the coiffure will retain its original appearance. Furthermore my hair form tends to hold the hair above the scalp which permits air to reach the scalp with beneficial results to the hair.

15 While I have shown my improved hair form in connection with a particular type of coiffure it is not so limited in its application, and it is obvious that various structural changes may be made therein without deviating from the spirit and scope of the appended claims.

I claim,

1. A form for dressing hair comprising a framework adapted to fit the head of a wearer, and yieldable hair supporting wire 25 members arching over said framework and adapted to spread apart under pressure.
2. A form for dressing hair comprising a framework adapted to fit the head of the wearer, and yieldable hair supporting wire 30 members arching over said framework and provided with corrugations for holding the hair in position said members being adapted to spread apart under pressure.
3. A form for dressing hair comprising a 35 framework adapted to fit the head of a wearer, and a corrugated hair supporting wire member arching over said framework, the said member being pivotally connected at its ends to said framework and being free 40 to yield at its middle.

MARY RUSSO.
